DENTAL LIGHT

Filed June 19, 1935

UNITED STATES PATENT OFFICE

2,038,911

DENTAL LIGHT

Adam Stutz and Jacob Milstead, Chicago, Ill.

Application June 19, 1935, Serial No. 27,346

2 Claims. (Cl. 240—2)

This invention relates to a novel and improved illuminating means particularly adapted for association with a dental drill, whereby desired and necessary illumination may be provided for the interior of the mouth of the patient while work is being performed upon him.

The main object of the invention is to provide in combination with a dental drill illuminating means so disposed as to provide illumination for the interior of the mouth, and novel and improved means for mounting said illuminating means in such manner as to give the desired result.

Another object of the invention is to provide novel and improved illuminating means associated with a dental drill for illuminating the interior of the patient's mouth, whereby overhead lights usually necessary in a dental office may be eliminated, resulting not only in a saving of electric current, but also eliminating the glare from said overhead lights with the added comfort to both the patient and the dentist.

A still further object of the invention is to provide novel and improved illuminating means for association with a dental drill to provide the desired illumination for the patient's mouth, which illuminating means may be readily attached to the drilling apparatus without necessitating an alteration or changing the construction of said apparatus.

Still another object of the invention is to provide illuminating means of the character described which will be simple in manufacture, assembly and operation, which may be constructed along lines convenient for low cost of production, and which, at the same time, will be highly efficient for carrying out the purposes for which it is designed.

With the foregoing and other objects in view, which will appear as the description proceeds, the invention consists in certain novel features of construction, arrangement and combination of parts, hereinafter more fully described, illustrated in the accompanying drawing, and particularly pointed out in the appended claims. It is to be understood that various changes in the form, proportion, size and minor details of the structure may be made without departing from the spirit or sacrificing any of the advantages of the invention.

For the purpose of facilitating an understanding of our invention, we have illustrated in the accompanying drawing a preferred embodiment thereof, from an inspection of which, when considered in connection with the following de-

scription, our invention, its mode of construction, operation and assembly, and many of its advantages should be readily understood and appreciated.

Referring to the drawing in which similar characters of reference are employed to indicate corresponding or similar parts through the several figures:

Figure 1 is a longitudinal sectional view through a dental drilling apparatus embodying our invention;

Figure 2 is a bottom plan view of the same;

Figure 3 is a transverse sectional view taken on line 3—3 of Figure 1;

Figure 4 is a transverse sectional view taken on line 4—4 of Figure 1;

Figure 5 is a transverse sectional view taken on line 5—5 of Figure 1;

Figure 6 is a transverse sectional view taken on line 6—6 of Figure 1;

Figure 7 is a fragmentary elevational view of Figure 1; and

Figure 8 is an enlarged sectional view of one of the spring contacts showing the method of contacting the lower terminal of the wires to the inverted cup members.

Referring to the drawing more specifically by characters of reference, the numeral 10, designates a bracket having the receptacle 11, adjacent one end thereof, the side flanges 12, extending longitudinally thereof, and a substantially circular portion 13, with an upward turned flange 56, having a hole to permit the passage of the screw 57, by means of which the ring 51, of insulating material, will be prevented from turning relative to the member 10. The substantially circular portion 13, is provided with the central opening 14. The receptacle 11, may be of conventional construction and has a pair of electric conductors 16, and 17, extending therefrom, said receptacle being adapted for cooperation with a suitable plug 18, connected to the conductor 19, for supplying the necessary current to the conductors 16, and 17.

An opening 20, is provided in the top 58, of the bracket 10, to permit the passage therethrough of the conductors 16, and 17, as shown in Figure 2.

The exposed portion of the conductors 16, and 17, are covered by a guard 65, which is made fast by means of its flange 66, and rivet 68, to the top 58, of the bracket 10, and by means of its side flanges 67 67, and rivets 69 69, to the side flanges 12 12, of the bracket 10.

The reference character 22, designates gener-

ally a hollow sleeve-like member provided with an enlarged suitable portion 23, adjacent its upper end and an enlarged cylindrical hollow portion 24, adjacent at its lower end. Within the 5 hollow portion 23, is mounted a suitable fibre piece 35, which is retained by means of the paste 59, to the bottom wall of receptacle 26, provided in the suitable portion 23.

Disposed within said suitable fibre piece 35, are 10 the conducting wires 30, and 31, respectively. The conducting wire 31, is soldered at its upper terminal to the contact spring 60, disposed within the receptacle 61, of the suitable fibre piece 35.

The bulb 36, disposed within a suitable cover 15 piece 62, made of brass, is adapted to make contact with the said spring 60, for the purpose of receiving the necessary electric current for illuminating the said bulb. The suitable cover piece 62, made of brass, is made fast to the suitable 20 piece 35, made of insulating material, by means of screws 63 63.

The conducting wire 30, terminates within the 25 groove 64, of the suitable piece 35, made of insulating material, adjacent to its top, and contacts with the suitable brass cover piece 62, by means of which the circuit is completed.

The said conducting wires 30, and 31, respectively, extend downwardly and are received in longitudinal grooves 32, and 33, respectively, provided in the interior of the hollow sleeve member 22, said conducting wires being adapted for making contact with the conductors 16, and 17, respectively, in the manner to be presently more fully described.

35 Disposed within the upper end of the sleeve member 22, is a tubular member 37, which member extends into said sleeve member 22, and has a press fit therein. The member 37, also projects beyond the upper end of the sleeve 22, as 40 shown in Figure 1, and is provided with a bore 74, extending completely therethrough through which extends the drill shaft 38, having a longitudinal hole 70, to the upper end of which is attached the drill 39.

45 The bulb 36, as will be noted from Figure 1, is so disposed as to provide the necessary illumination for the interior of the patient's mouth when the drill is in operative position within the patient's mouth. The drill shaft 38, extends 50 through the sleeve 22, and through a member 40, which is received in the lower portion of the sleeve 22, said member 40, also having a press fit within the interior of said sleeve 22. The screw 13, disposed within the enlarged cylindrical hollow portion 24, of the hollow sleeve like 55 member 22 retains the member 40, in its place.

To complete the assembly of our improved device, there is mounted within the hollow interior of the enlarged portion 24, of the sleeve 22, a 60 fibre ring 41, provided with the recesses 42, and 43, respectively. Disposed within said recesses 42, and 43, are inverted cup members 44, and 45, respectively, said cup members being of conducting material, and being arranged in contacting engagement with the wires 30, and 31, respectively, as shown in Figure 8. Disposed within each of the cup members 44, and 45, is a coil spring 46, and surrounding said coil spring are inner cup members 47, and 48, respectively.

70 The said inner cup members 47, and 48, being received within the inverted cup members 44, and 45, whereby the springs 46, will be confined between the inverted and the inner cup members, as shown in Figure 8.

75 The inner cup members 47, and 48, respectively,

are in constant contacting engagement with the semi-circular rings 49, and 50, respectively, which rings are made of suitable conducting material and are disposed within recesses provided therefor in the ring 51, of insulating material. Said 5 members 49, and 50, are insulated from each other by means of the portions 52, and 53, of the insulating material of the ring 51, as shown on Figure 6 of the drawing.

The insulating ring 51, is provided with a de- 10 pending flange portion 75, of reduced diameter, which has a press fit within the opening 14, of the bracket 10.

The member 51, has the conductors 16, and 17, respectively, passed therethrough, the end of said 15 conductors being disposed within the grooves 71, and 72, respectively, adjacent to the bottom of the semi-circular rings 49, and 50, respectively, and the member 51, whereby a good contact will be had between the conductors 16, and 17, and the 20 semi-circular members 50, and 51, respectively.

It will be apparent that when in assembled position, the members 49, and 50, respectively, will be in contacting engagement with the inner cup members 47, and 48, respectively, by reason of 25 the springs 46, said springs also being effective to carry the current by means of the inverted cup members 44, and 45, respectively, to the lower terminals of the conductors 30, and 31, respectively. The upper terminals of the conductors 30 30 30, and 31, respectively, are disposed within the fibre piece 35, which through the medium of the member 62, will complete the circuit to the bulb 36, for illuminating the same.

From the above it will be apparent that we 35 have produced a device which will be highly efficient for producing the desired illumination within the interior of the patient's mouth, thereby eliminating the necessity for the conventional overhead lights with the resulting comfort to 40 both the dentist and the patient.

It will also be noticed that we have provided 45 a novel and improved contact means for the current conducting members which will not be jarred out of contacting engagement by reason of the vibration present in devices of this character. It will also be noted that the device is one which may be produced commercially at a low cost and at the same time be simple in its 50 assembly and operation.

It is believed that our invention, its mode of construction, and many of its advantages should be readily understood from the foregoing without further description, and should also be manifest that while a preferred embodiment of the 55 invention has been shown and described for illustrative purposes, the structural details are, nevertheless, capable of wide variation within the purview of our invention as defined in the appended claims.

Having described our invention, what we claim 60 and desire to secure by Letters Patent of the United States is:

1. The combination with a dental drill, of a sleeve-like member surrounding the same, a hollow suitable portion provided on said sleeve-like member adjacent the upper end thereof, an electric bulb disposed within said hollow suitable portion and arranged parallel with the axis of 65 said drill, a second hollow cylindrical portion 70 provided at the other end of said sleeve-like member, spring pressed contacts provided therein and insulated from the body of the member, electric current conductors connecting said spring pressed contacts with the bulb, fixed contacting members 75

arranged below said spring pressed contacts, electric conductors connected to said fixed contacting members, said last mentioned conductors being connected to a supply of electric current.

- 5 2. In combination with a dental drill, of illuminating means associated with said drill for producing illumination within the interior of the patient's mouth, said illuminating means comprising a bulb arranged adjacent parallel with 5
10 the axis of the drill, and means for supplying electric current to said bulb, said means including a pair of conductors leading from a source

of current, a guide for said conductors, fixed semi-circular conducting rings connected with said conductors, spring contacts in constant engagement with said fixed semi-circular rings, a second pair of conductors having one of the terminals connected to said spring contacts, the other of the terminals of said last mentioned conductors being disposed in position for completing the circuit of the illuminating bulb.

ADAM STUTZ. 10
